[57] CLAIM

The ornamental design for an incontinence pad, as shown and described.

DESCRIPTION

FIG. 1 is an isometric view of the top and one side of a preferred embodiment of our design for an incontinence pad;

FIG. 2 is a top view of a preferred embodiment of our design;

FIG. 3 is a side view of a preferred embodiment of our design;

FIG. 4 is an end view of a preferred embodiment of our design; and,

FIG. 5 is a bottom view of a preferred embodiment of our design.

The side not shown is identical to that shown in FIG. 3. The end not shown is identical to that shown in FIG. 4.

FIG. 2

FIG. 3
